(57) **CLAIM**

The ornamental design for a fastening device, as shown and described.

DESCRIPTION

FIG. 1 is a perspective view of a fastening device in accordance with my new design;

FIG. 2 is a right side elevation view thereof, wherein a left side elevation view is a mirror image of the right side elevation view;

FIG. 3 is a front elevation view thereof;

FIG. 4 is a rear elevation view thereof;

FIG. 5 is a top plan view thereof;

FIG. 6 is a perspective view of a fastening device in accordance with another embodiment of my new design;

FIG. 7 is a right side elevation view thereof, wherein a left side elevation view is a mirror image of the right side elevation view;

FIG. 8 is a front elevation view thereof;

FIG. 9 is a rear elevation view thereof; and,

FIG. 10 is a top plan view thereof.

The broken lines in the figures illustrate portions of the fastening device that form no part of the claimed design. The bottom plan view forms no part of the claimed design.

1 Claim, 10 Drawing Sheets
